CERAMIC TILE TRIM FOR A LAVATORY BASIN, OR THE LIKE

Joseph Stephen Wheeler, Jr., Anaheim, Calif. (½ Huntington Tile, Inc., 9223 Bolsa Ave., Westminster, Calif. 92683)

Original design application Dec. 29, 1966, Ser. No. 5,222.
Divided and this application Oct. 28, 1968, Ser. No.
14,204

Term of patent 14 years

Int. Cl. D25—01

U.S. Cl. D18—2

FIG. 1.

FIG. 2.

FIG. 3.

FIG. 1 is a perspective view of a ceramic tile trim for a lavatory basin, showing my new design;

FIG. 2 is a top plan view thereof; and,

FIG. 3 is a cross-sectional view taken on line 3—3 on FIG. 2.

This is a division of design application Ser. No. 5,222, filed Dec. 29, 1966.

I claim:

The ornamental design for a ceramic tile trim for a lavatory basin, or the like, as shown and described.
